(No Model.)

J. THOMSON.
DISK WATER METER.

No. 568,642.

Patented Sept. 29, 1896.

Fig. 1.

UNITED STATES PATENT OFFICE.

JOHN THOMSON, OF BROOKLYN, NEW YORK, ASSIGNOR TO THE NEPTUNE METER COMPANY, OF JERSEY CITY, NEW JERSEY.

DISK WATER-METER.

SPECIFICATION forming part of Letters Patent No. 568,642, dated September 29, 1896.

Application filed March 28, 1896. Serial No. 585,270. (No model.)

To all whom it may concern:

Be it known that I, JOHN THOMSON, a citizen of the United States, residing at Brooklyn, in the county of Kings and State of New York, have invented certain new and useful Improvements in Disk Water-Meters, of which the following is a specification.

My present invention relates to disk water-meters, and has special reference to the manner of constructing and arranging the socket-bearing for the ball supporting the disk, and it has for its object to provide a construction and arrangement of parts adapted for the employment of a material having a low coefficient of friction; and to these ends my invention consists in the various features of construction and arrangement of parts, substantially as hereinafter set forth.

In the accompanying drawings I have illustrated an embodiment of my invention and shown sufficient details to enable those skilled in the art to make and use the same, and in said drawings—

Figure 1 is a vertical central section through a disk-chamber casing, showing the ball and disk in full lines. Fig. 2 is a vertical section of the socket-bearing, showing the details of construction in the preferred form; and Fig. 3 is a similar view showing a modification in the construction of the socket-bearing.

As is well known to those skilled in the art relating to disk water-meters, it is exceedingly desirable that the disk and its attached parts shall be as free to move as possible and be subject to little friction and wear, in order that the meter may continue to operate with absolute freedom and register with great accuracy, and I attain this main object in the present instance by a construction and arrangement of parts well adapted to make use of a material or bearing having a low coefficient of friction, and consequently little wear, and at the same time to make an exceedingly cheap, simple, and efficient application of the same. There are numerous materials in the market having this general characteristic, such, for instance, as compounds of graphite and similar substances, and these materials are furnished to the trade in certain well-known forms, such, for instance, as tubes or hollow cylinders of various sizes, and it is

with special reference to adapting my invention to the utilization of such tubes that the present construction is made, having in view economy as well as efficiency.

55

In the embodiment of my invention (shown in the accompanying drawings) the disk-chamber casing of the meter is made up of upper and lower sections 6 and 7, united in any usual way, forming the disk-chamber 1, 60 and one of the sections, as the lower section 7, is provided with a projection 8, preferably cylindrical in form, and in this disk-chamber is mounted the disk 9, supported on the ball 10 and having the usual spindle 5 projecting 65 through an opening 2 in the upper section. The socket-bearing B is preferably made as a separate and independent structure adapted to fit in the projection 8 of the casing, and, while it may be variously formed, I prefer to 70 use an outer shell 12 of metal and an inclosing head 13, which latter forms or supports the metallic portions of the socket-bearing, as well as the antifriction compound, and this latter is preferably arranged in the form 75 of concentric rings 14 of solidified graphite compound. These rings fit in recesses or grooves in the inclosing head 13, and are also supported in position by the outer metallic shell 12. This shell 12 is preferably formed 80 with its upper edge 15 arranged at an angle similar to that of the lower frustum 16 of the disk-chamber, and the interior flange 17 preferably corresponds thereto, thus providing an efficient means of supporting the outer 85 ring or portion of antifriction material. In making this form of socket-bearing the recesses or grooves in the head are made of the desired shape or form, preferably such as will receive the rings or portions cut from cylindrical bushings, and these are first pressed into the recesses in the head, when the latter, with the attached rings, is inserted into the shell and forced up snugly against the seat or flange 17, and the head may be secured in 90 the shell. The interior of the socket-bearing then presents the sharp edges of the inner portions of the rings or bushings, as indicated in dotted outlines 18, Figs. 2 and 3, and the final operation is to reduce these sharp edges 95 to the proper form, which may be done by chucking the socket and turning out the ma 100

terial to the desired spherical contour in any suitable and well-known way. This will present a socket-bearing having alternate faces of metal and antifriction material in the form 5 of concentric rings; but to relieve the ball 10 of all metallic bearing the rings or ridges of metal may be slightly recessed, as indicated at 19.

Obviously, the cylindrical rings or bushings 10 may all be inserted from above into a single head, as indicated in Fig. 3, the head being recessed or grooved, so that the rings are without metallic separation, the bushings being "nested" one within the other, and when 15 the final operation is completed they present a practically continuous face of antifriction material. I prefer, however, a construction similar to that indicated in Figs. 1 and 2 for hard service and best results, in that the 20 fragile antifriction material is better supported and less liable to crumble and escape when the intervening metallic rings or bearing portions 19 are used.

As is well known, it is somewhat difficult 25 to machine compounds of graphite to a uniformly accurate gage, as the cutting-points of the tool soon become glazed and dull. Hence to obviate this difficulty I find it advantageous to machine the socket-bearing to 30 an approximate size and shape, but less in diameter than that of the accurately-formed metal ball 10, used in connection with the bearing, and I then provide the ball with depressions—as, for instance, a groove 20—the 35 sharp edges of which, when the ball is in position and oscillated in its usual operation, produce a shear action upon the antifriction compound, quickly resulting in reducing the socket-bearing to the proper size and furthering a complete and uniform bearing-surface for the ball, and I have found that the 40 action of the antifriction compound on the edges of the groove will soon dull them and prevent undue removal of the material. The 45 ball is preferably provided, as indicated in the drawings, with a helical or spiral groove 20, as this form apparently gives the best results.

Having thus explained the nature and object 50 of my invention and pointed out the pre-

ferred manner of embodying the same, it will be understood that I do not limit myself to the precise details of construction and arrangement of parts, as these can be varied by those skilled in the art to suit the circumstances of any particular construction of meter.

What I claim is—

1. In a disk water-meter, a socket-bearing for the ball comprising a shell, a head, and 60 a plurality of concentric bushings of antifriction compound, substantially as described.

2. In a disk water-meter, the combination with the disk-easing, the disk and the ball, of the shell, the head, and the concentric 65 rings of graphite compound, substantially as described.

3. In a disk water-meter, the combination with the disk-easing, the disk and the ball, of a socket-bearing comprising a shell having 70 an internal flange, a head provided with recesses, and concentric blocks of graphite compound mounted in said recesses, substantially as described.

4. In a disk water-meter, the combination 75 with the disk-easing, the disk and the ball, of a detachable socket-bearing comprising a shell, and a head with a plurality of concentric recesses and with rings of graphite compound mounted therein, substantially as de- 80 scribed.

5. In a disk water-meter, the combination with a socket-bearing provided with antifriction material, of a ball, the surface of the ball in contact with the antifriction material 85 being provided with depressions, substantially as described.

6. In a disk water-meter, the combination with a socket-bearing provided with antifriction material, of a ball, the surface of the 90 ball in contact with the antifriction material being provided with a helical groove, substantially as described.

In testimony whereof I have signed my name to this specification in the presence of 95 two subscribing witnesses.

JOHN THOMSON.
